UNITED STATES PATENT OFFICE.

DAVID E. BRANDT, OF CHISAGO CITY, MINNESOTA.

TELLURIAN.

1,045,807.

Specification of Letters Patent.

Patented Dec. 3, 1912.

Application filed May 5, 1911. Serial No. 625,197.

To all whom it may concern:

Be it known that I, DAVID E. BRANDT, a citizen of the United States, residing at Chisago City, in the county of Chisago and State of Minnesota, have invented certain new and useful Improvements in Tellurians; and I do hereby declare the following to be a full, clear, and exact description of the invention, such as will enable others skilled in the art to which it appertains to make and use the same.

My invention has for its object to provide a simple and efficient tellurian or instrument for showing the operation of the causes which produce the succession of day and night and the changes of the seasons.

The invention is illustrated in the accompanying drawings wherein like characters indicate like parts throughout the several views.

Referring to the drawings,—Figure 1 is a plan view of the apparatus; Fig. 2 is a view chiefly in side elevation with some parts in vertical section taken centrally through the apparatus; Fig. 3 is an enlarged view partly in elevation and partly in vertical section and with some parts broken away showing the rotatable crank mechanism and part of the orbital table of the apparatus. Fig. 4 is a fragmentary detail partly in side elevation and partly in vertical section showing the connection between the globe supporting arm and the globe; and, Figs. 5 and 6 are detail views in horizontal section taken on the line $x^5 x^6$ of Fig. 4.

The numeral 1 indicates a supporting pedestal having an expanded base 2 and a prong head 3. To the prongs of the head 3, a hub or sleeve 4 is connected by a horizontal pivot 5.

The numeral 6 indicates a so-called orbital table shown as in the form of a disk rigidly secured to a large non-rotary gear 8 which, in turn, is secured by bolts 7, or otherwise, to a flange of the hub 4'. On the upper face of the table 6 is a dial 9 which is graduated and marked to indicate the months, the seasons, the degrees of the earth's orbit and various other data relating to the revolution of the earth around the sun. This dial 9 is preferably printed on a dial plate or disk that is secured to the table 6, but it may, when desired, be marked or stamped directly on the said table.

The orbital table 6 is adapted to be set at different inclinations and is assumed to ex-

tend in a plane parallel to the plane of the earth's orbit. For adjustably supporting the table 6 in different or in any desired angular position, its hub 4 is shown as provided with an arm 11 that is connected by a link 12 to a head 13 mounted to slide vertically on the pedestal 1 and adapted to be secured in any set adjustment on the said pedestal by a clamping screw 14.

The numeral 15 indicates a crank shaft that is extended through and journaled on the hub 4 and, as shown, is provided at its lower end with an operating crank 16. To the upper end of the crank shaft 15 are rigidly secured two radially projecting arms 17 and 18. The free end of the arm 18 is in the form of an inverted channel, and is telescoped over a similar channel-shaped arm extension 19 that is longitudinally adjustable in respect thereto and adapted to be held in different adjustments by a set screw 20. The free end of the arm extension 19 is in the form of a hollow annular head 21 that is flattened in the plane of rotation of the arms 18—19. In its top face, the head 21 is provided with a quite large axial opening 21^a that is surrounded by a flat annular bearing surface or tract 21^b.

The lower face or bottom of the head 21 is formed by a flanged detachable cap 22 having a large axial opening 22^a and an extended arm 23, which latter affords a finger or hand piece by means of which, as well as by the crank 16, the globe supporting arms 18—19 may be rotated. To detachably hold the cap 22 interlocked to the head 21, the former is shown as provided with a radially projecting stud 24 that is insertible through a notch 25 in the bottom of the head 21 and is engageable with a segmental cam groove 26 formed in one side of the said head 21, as best shown in Figs. 5 and 6.

The globe 27, representing the earth, is provided with a spindle 28 projecting from its poles and provided on its depending end with a small sheave 29 and with a supporting flange or head 30. The spindle 28 is extended through the axial perforations 21^a and 22^a and the sheave 29 is located within the head 21 while the supporting flange or head 30 runs upon the supporting surface or tract 21^b.

The passages 21^a and 22^a are of such diameter and are so related to the spindle 28, and to the inclination of the plane of rotation of the arms 18—19, that the globe 27

will be gravity held with its axis in an oblique position, corresponding to the actual inclination of the earth's axis in respect to its orbit, and throughout the rotations of the 5 said arm, the axis of the globe 27 will be gravity held always parallel to any assumed initial position.

To represent the sun, a suitable source of light is applied to the arm 18 at or near the 10 axis of rotation. As shown, this source of light representing the sun is afforded by a small lamp 31, such, for instance, as is used in connection with bicycles and for similar purposes. This lamp, of course, rotates 15 with the arm 18 and its light will be constantly directed upon the globe 27 so as to produce the desired light and shadow effect on the globe.

The globe 27 is rotated on its own axis 20 365 times for each revolution that it makes around the artificial sun. This rotation of the globe may be accomplished in various ways, but, as shown, is accomplished as follows: The crank arm 17 carries a gear supporting bracket 32, one arm of which is 25 shown as adjustably secured to the said arm 17 by a set screw 33. The bracket 32 carries two parallel oblique counter shafts 34 and 35. The counter shaft 34 is provided with 30 a spur pinion 36 that meshes with the large non-rotary gear 8, and it is provided with a spur gear 37 that meshes with the small spur pinion 38 carried by the shaft 35. The shaft 35 at its upper end carries a driving 35 sheave 39. A driving belt 40 runs over the sheave 39 and over the relatively small sheave 29 of the globe spindle 28. This belt 40 is passed through the outer end portion 40 of the crank arm 18, between the guide rollers 18^a on said arm 18, and through the arm extension 19. Furthermore, the bracket 32 preferably carries a pointer finger 41 that moves over the outer graduated portion of the dial 9 and cooperates therewith to indicate 45 the positions of the earth in its travel on its orbit. By outward radial adjustments of the brackets 32 in respect to the arm 17, the pinion 36 may be disengaged from the gear 8 so that when desired, the 50 globe may be revolved in its orbit without rotation on its own axis. By adjustments of the arm extension 19 in respect to the arm 18, the driving belt 40 may be properly adjusted for its traveling action on the sheave 29. As is evident, only a slight friction will 55 be required to rotate the globe on its axis.

What I claim is:

1. In a tellurian, the combination with an inclined shaft having an arm arranged to 60 rotate in an inclined plane and provided at its end with a perforated head, of a globe having a depending spindle loosely mounted for wabbling pivotal movement in the said perforated arm head, whereby said globe through its orbital movement will be held

with its axis inclined approximately in a constant direction, and means for rotating said globe on its axis under pivotal movement of said supporting arm.

2. In a tellurian, the combination with a supporting arm mounted to rotate in an inclined plane, of a globe having a spindle loosely connected to said arm by a wabbling pivot joint, whereby the globe under its orbital movement will be gravity held with its axis inclined approximately in a constant direction, a bearing for the said supporting arm adjustable to vary the inclination of the plane in which the said arm rotates, and means for rotating said globe on its axis under pivotal movement of the said supporting arm.

3. In a tellurian, the combination with an inclined shaft having an arm arranged to rotate in an inclined plane and provided at its end with a perforated head, of a globe having a depending spindle loosely mounted for wabbling pivotal movement in the said perforated arm head, whereby said globe through its orbital movement will be held with its axis inclined approximately in a constant direction, means for rotating said globe on its axis under pivotal movement of said supporting arm, and a bearing for the said supporting arm adjustable to vary the inclination of the plane in which the said arm rotates.

4. The combination with an orbital table having a graduated dial and a non-rotary gear fixed in respect thereto, of an inclined crank shaft journaled at the center of said table and provided with a radial globe supporting arm terminating in a perforated bearing head, a globe having a spindle loosely seated for a wabbling pivotal movement in the said bearing head and gravity held throughout its orbital movement with its axis approximately at a constant inclination, a sheave carried by the said globe spindle, a bearing bracket carried by said crank shaft, a sheave carried by said bracket, gears and shafts carried by said bracket and serving to drive said latter sheave from said non-rotary gear and a belt running over the two sheaves noted, substantially as described.

5. The combination with an orbital table having a graduated dial and a non-rotary gear fixed in respect thereto, of an inclined crank shaft journaled at the center of said table and provided with a radial globe supporting arm terminating in a perforated bearing head, a globe having a spindle loosely seated for a wabbling pivotal movement in the said bearing head and gravity held throughout its orbital movement with its axis approximately at a constant inclination, a sheave carried by the said globe spindle, a bearing bracket carried by said crank shaft, a sheave carried by said bracket,

gears and shafts carried by said bracket and serving to drive said latter sheave from said non-rotary gear, a belt running over the two sheaves noted, and a source of light carried by the said crank shaft and representing the sun.

6. In a tellurian, the combination with a supporting pedestal of an orbital table pivotally supported thereby, a connection between said table and pedestal for varying the angle of inclination of the former, an inclined crank shaft journaled at the center of said table and provided with a globe supporting arm, a globe having a spindle connected to said arm by a wabbling pivotal joint and gravity held approximately in a constant oblique position, means for rotating said globe on its own axis under rotation of said supporting arm, and a lamp carried by the said supporting arm and representing the sun.

10 7. In a tellurian, the combination with a supporting pedestal of an orbital table pivotally supported thereby, a connection between said table and pedestal for varying the angle of inclination of the former, an inclined crank shaft journaled at the center of said table and provided with a globe supporting arm, a globe having a spindle connected to said arm by a wabbling pivotal joint and gravity held approximately in a constant oblique position, means for rotating said globe on its own axis under rotation of said supporting arm.

15 8. In a tellurian, the combination with a supporting pedestal of an orbital table pivotally supported thereby, a connection between said table and pedestal for varying the angle of inclination of the former, an inclined crank shaft journaled at the center of said table and provided with a globe supporting arm, a globe having a spindle connected to said arm by a wabbling pivotal joint and gravity held approximately in a constant oblique position, means for rotating said globe on its own axis under rotation of said supporting arm.

20 9. In a tellurian, the combination with a supporting pedestal of an orbital table pivotally supported thereby, a connection between said table and pedestal for varying the angle of inclination of the former, an inclined crank shaft journaled at the center of said table and provided with a globe supporting arm, a globe having a spindle connected to said arm by a wabbling pivotal joint and gravity held approximately in a constant oblique position, means for rotating said globe on its own axis under rotation of said supporting arm, and a lamp carried by the said supporting arm and representing the sun.

10 10. In a tellurian, the combination with a supporting pedestal of an orbital table pivotally supported thereby, a connection between said table and pedestal for varying the angle of inclination of the former, an inclined crank shaft journaled at the center of said table and provided with a globe supporting arm, a globe having a spindle connected to said arm by a wabbling pivotal joint and gravity held approximately in a constant oblique position, means for rotating said globe on its own axis under rotation of said supporting arm, and a lamp carried by the said supporting arm and representing the sun.

15 11. In testimony whereof I affix my signature in presence of two witnesses.

DAVID E. BRANDT.
